COATING ARTICLES WITH AN IMPERMEABLE CLOTH, FELT, OR THE LIKE

Joseph Francis Strable, Strood, England, assignor
to Gyproc Products Limited, London, England,
a company of Great Britain

Application December 20, 1941, Serial No. 423,762
In Great Britain April 18, 1941

13 Claims. (Cl. 154—36)

This invention relates to the coating of the surfaces of articles, which are pervious to moisture or liable to deterioration when exposed to moisture, with an impermeable covering of felt, cloth, or other flexible sheet material impregnated with or consisting of a substance which becomes tacky when heated, for the purpose of rendering the articles unaffected by moisture. The invention is especially but not exclusively concerned with the application of bitumen felt to the surfaces of panels or boards such for example as plaster boards.

Bitumen felt is commonly bonded to surfaces by the agency of hot or cold adhesives such as glues, resins or pitch. Since the object of coating articles with bitumen felt is to render them resistant to the effects of water, waterproof adhesives have been used. Since, however, bitumen felt and like sheet coating materials already incorporate an adhesive substance which is inherently waterproof, the use of an additional waterproof adhesive for the purpose of bonding the sheet material to the surface to be coated involves waste, and it is an object of this invention to avoid such waste by dispensing with any additional adhesive.

In the manufacture of bitumen felt it is usual to roll the felt when it is still warm, and, although while being so rolled it is sprayed with powdery substances to free it from tackiness, it nevertheless is seldom completely free therefrom but when being unrolled for use it generally will cling tenaciously and unequally over its surface with the result that the unrolled length tends to deviate from a straight path. Moreover, bitumen felt, after having been unrolled and laid in position, will gradually extend over a period which may amount to several days, and this is apt to cause it to set in corrugations.

A further object of this invention is to overcome these difficulties.

Bitumen felt is commonly transported in rolls containing a relatively short length, for example 75 feet, and it is seldom that the length of felt in a roll is an integral multiple of the length of each of a succession of similar boards required to be coated with the felt. Consequently either an end portion of each roll must be cut to waste, or a joint must be made in the felt; and accordingly it has not hitherto been possible to coat a series of boards with bitumen felt without relatively frequent interruptions to the sequence of operations when a fresh roll of felt is brought into use. Another object of the present invention is to enable a series of boards to be coated

with flexible sheet material such as bitumen felt without interruption to the continuity of the process.

Further objects and advantages of the invention will be apparent from the following description of an embodiment thereof adapted to secure a continuous length of bitumen felt to a succession of boards, this description being given with reference to the accompanying drawings, in which—

Fig. 1 is a longitudinal section of apparatus in accordance with the invention, taken on the line 1—1 of that part of the apparatus appearing in Fig. 4.

Fig. 2 and 3 are respectively sections on the lines 2—2 and 3—3 in Fig. 1.

Fig. 4 is a plan, with certain elements in section, of a part of the apparatus shown in Fig. 1.

Fig. 5 is a side elevation, with certain elements in section, of the part shown in Fig. 4.

Fig. 6 is an elevation of the same part, as seen from the opposite side, also with certain parts in section.

Fig. 7 is an elevation of part of a gas burner tube, and

Fig. 8 is a view of a portion of a scraper.

The frame of the machine is mounted on two longitudinal rolled steel channel sleepers, one of which appears at 10 in Fig. 1, supporting a plurality of angle section posts 11 and a pair of cast-iron sub-frames 12 and 13. The frame supports a horizontal feed path for plaster boards consisting of a series of rollers 14 and 14A at the entry portion of the path and 15 at the discharge portion of the path. The rollers 14 and 14A are journalled in two horizontal angle bars 16 and 17 fixed respectively to brackets 18 and 19 mounted on the sub-frames 12 and 13. The rollers 15 are journalled in two horizontal angle bars 20 and 21 fixed to the sub-frames 12 and 13, to a transverse angle bar 22, and to transverse angle bars 26 fixed to the posts 11. The posts 11 support an upper feed path for bitumen felt, which path includes two longitudinal angle bars 23 and 24 which are carried on transverse angle bars 25 fixed to the posts 11. Near the sub-frames 12 and 13 the bars 23 and 24 of the upper path are inclined downwards, and their ends are fixed to struts 27 and 28 supported on the bars 20 and 21. The middle portion of the upper path is floored with transverse timber boards 29 (Figs. 1 and 3) fixed to timber runners 30 and 31 in turn fixed to the bars 23 and 24. A timber beam 32 having a sloping upper face forms the end of this floor remote from the sub-frames.

The timber floor is provided with fences 33 and 34 adjustably held by bolts 35 fitted through transverse slots 36 in the boards 29.

Near the end of the upper path remote from the sub-frames are mounted on the bars 23 and 24 respectively two half bearings 37 and 38 (Fig. 2) carrying a shaft 39 for supporting a roll 40 of bitumen felt. Two tapered plugs 41 are slideable on the shaft 39 and are provided with set screws 42 whereby they may be locked to the shaft after they have been forced into the ends of the core of the felt roll. The shaft 39 is capable of sliding in the bearings 37 and 38 for the purpose of adjusting the position of the roll 40 transversely, and it is provided with collars 43 fitted with set screws 44 and adapted to abut against the bearings, so that the roll can be maintained in the desired position of transverse adjustment.

Adjacent to the felt roll is a transverse tensioning member 45 (Fig. 1) which may be a bar 20 fixed to or a roller rotatably mounted on the longitudinal bars 23 and 24.

The sub-frames 12 and 13 support the pressure roll mechanism, which includes two hollow metal rolls 46 and 47 disposed one above the other. The lower roll 47 is journaled in bearings 48 and 49 fixed to the sub-frames 12 and 13 respectively, while the upper roll 46 is journaled in bearings 50 and 51 which are capable of adjustment vertically so as to vary the depth of the gap between the rolls. The means for effecting this adjustment are identical at the two sides of the machine, and they will be described with reference to bearing 50 and Fig. 5. The bearing 50 is integral with a cylindrical sleeve 52 slideable on a vertical tube 53 fixed to the sub-frame 12. A nut 54 is fixed to the sleeve 52 by a radial projection 55 fitting within a vertical slot 56 in the tube 53. The nut 54 co-operates with a lead screw 57 journaled in a bearing 58 retained within the upper end of the tube 53 by a cap 59 which is split at 61 and clamped by a stud 60. A worm wheel 62 keyed to the lead screw 57 meshes with a worm 63 keyed to a transverse shaft 64. The shaft 64 is provided with a handle 65 and is common to the roll-adjusting means at the two sides of the machine, so that the roll 46 is constrained to remain parallel to the roll 47 at all times.

The upper roll 46 is arranged to be artificially cooled by water which is admitted at a gland union 66 to a bore 67 (Fig. 4) in the shaft 68 of the roll 46 and thence through a port 69 to the interior of the roll. A similar arrangement exhausts heated water at a gland union 70 at the other side of the apparatus.

A steel scraper blade 71 (Figs. 5 and 8) is bolted to an angle bar 72. Pivot pins 73 welded to the ends of the bar 72 are journaled in extensions 74 and 75 of the bearings 50 and 51. A weighted lever 76 urges the edge of the blade 71 resiliently against the surface of the roll 46. The scraper also carries a wiper strip 77 of felt having a free edge resting against the roll 46 above the blade 71. The roll in rotating frictionally engages this edge of the wiper strip which is thereby kept in trough section. A perforated pipe 78 disposed above this trough is arranged to deliver a row of water jets into the trough whereby the felt is kept moist and the roll 46 is externally cooled. A valve 79 controls the flow of water to the pipe 78. A similar scraper 80, journaled in extensions of the bearings 48 and 49, is resiliently engaged by means of a weighted lever 81 with the surface of the lower roll 47 which dips into a water bath 82 (Fig. 1). A rubber squeegee 83 is provided on this

scraper for the purpose of removing excess water from the surface of the roll.

The pressure rolls 46 and 47 are driven by chain sprockets 84 and 85 (Fig. 6) and a chain 86 engaging with a driving sprocket 87 and a jockey sprocket 88. The sprocket 87 is fast on a countershaft 89 forming the output shaft of a worm reduction gearing 90, the input shaft 91 of which is connected, through a change-speed gear 92 of continuously variable ratio having a driving shaft 93 to a motor (not shown).

If desired, the roller 14A on the lower path may be power driven from the counter shaft 89 by a sprocket 94 fixed to this shaft, a chain 95, and a sprocket 96 rigid with a sleeve 97 rotatable on the shaft 98 of the roller 14A. The sleeve 97 is connected to the shaft 98 by a roller free wheel clutch 99 capable of rotating the roller 14A clockwise as viewed in Figs. 1 and 5. Additional rollers similar to roller 14A and disposed along the length of the path may be driven through similar free wheel clutches. The drive to the next roller is taken by a chain 100 engaging with a sprocket fast on the sleeve 97. The peripheral speed of the roller 14A slightly exceeds the peripheral speeds of the rolls 46 and 47 which rotate at the same speed.

At the end of the upper feed path adjacent to the pressure rolls is disposed a device for stretching the bitumen felt. This device consists of a plurality of transverse tensioning members mounted in a swivelling frame which is normally rigidly fixed on the angle bars 23 and 24. The swivelling frame consists of side angle bars 101 and 102 (Figs. 4 and 5) rigidly braced by transverse rods 103 and 104. Rollers 105 and 106 are journaled on the two rods 104. The roller 106 is provided with a flange 107, the inner face 108 of which is accurately aligned with the inner face 109 of a fence 110 fixed to the angle bar 17 of the entry portion of the lower feed path. The roller 106 is furthermore provided with an adjustable collar 111 adapted to be locked by a set screw 112. A bar 113, disposed parallel to and 43 between the rollers 105 and 106, is fixed to lugs 114 projecting from two levers 115 pivoted at 116 on the side bars 101 and 102. Each lever 115 carries a lateral blade 117 which co-operates with a serrated quadrant arm 118 fixed to the adjacent side bar. By adjusting the levers 115 along the quadrants 118, the bar 113 of the stretching device can be raised and lowered. The stretching device is capable of a swivelling motion about a pivot pin 119 by which the side bar 102 55 is secured to the bar 24 of the upper feed path. This swivelling motion is limited by pins 120 mounted in the bar 23 of the upper path and passing through slots 121 in the side bar 101. Swivelling is controlled by a lever 122 which is 60 pivoted at 123 to a bracket 124 fixed to the bar 23. A pin 125 couples the lever 122 to a bracket 126 fixed to the side bar 101. The lever 122 can be locked, in the neutral position shown, by a small pin 127 accurately fitted in registering holes 65 in this lever and in the bracket 126, in order to lock the stretching device in a position such that the rollers 105 and 106 are exactly parallel with the pressure rolls.

A gas burner is constituted by a tube 128 disposed parallel to the pressure rolls, close to the upper of these rolls, and close to the horizontal plane defined by the tops of the rollers of the lower feed path. The tube 128 is perforated over a length corresponding with the width of the bitumen felt. The preferred arrangement of per-

forations is as shown in Fig. 7, namely, two rows of holes $\frac{1}{8}$ inch in diameter, the holes being spaced at intervals of $\frac{1}{2}$ inch along each row and being uniformly staggered with respect to the holes in the adjacent row, and the rows being $\frac{1}{4}$ inch apart. The burner tube 128 is supported in two bearers 129 secured respectively to the brackets 18 and 19 by screws 130 engaged in the brackets and passing through slots 131 in the bearers, this arrangement permitting the burner tube to be adjusted to various positions longitudinally of the machine. The burner tube is furthermore capable of angular adjustment about bearings in the bearers, under the control of a lever 132, between a position in which the flames are directed substantially horizontally towards the roll 46 and a position in which the flames are directed upwardly clear of this roll. The burner tube is supplied with combustible mixture through a swiveling union 133 and a hose 134 leading to an injector 135 (Fig. 1) supplied with coal gas at 136 and compressed air at 137.

The operation of this apparatus will now be described. Figs. 1, 2, 3, 5 and 6 show the machine with plaster boards and bitumen felt in positions which they occupy when the machine is running, whereas in Fig. 4 the boards and felt are not shown.

In setting up the machine for operation, the collar 111 on the roller 106 of the stretching device is spaced from the flange 107 on this roller by a distance exactly equal to the width of the bitumen felt. The fences 33 and 34 on the upper feed path are substantially aligned with the inner faces of the collar 111 and the flange 107, but spaced slightly farther apart so as to provide a small clearance, of the order of $\frac{1}{16}$ inch, at each side between the fences and the bitumen felt when the latter is running true. A roll of felt is mounted on the shaft 39, aligned with the fences, and secured laterally by locking the collars 43. The handle 65 is operated to set the gap between the pressure rolls 46 and 47 to more than the combined thickness of a plaster board and the bitumen felt. A plaster board is placed on the entry portion of the lower path, pushed laterally against the fence 110, and then slid longitudinally until its leading end border is between the pressure rolls. The end of the felt strip is unwound from the roll 40, passed under the tension bar 45, between the fences 33 and 34 on the upper feed path, over the rollers 105 and 106 and under the bar 112 of the stretching device and round one half of the circumference of the pressure roll 46, its leading edge being placed over the leading edge of the plaster board. The handle 65 is now operated to lower the roll 46 until the felt and the board are nipped between the pressure rolls. The cooling water feeds having been turned on, the gas burner is ignited and the handle 132 is operated to direct the flame towards the felt. The burner perforations are now spaced about $2\frac{1}{2}$ -3 inches from the surface of the felt on the roll 46, the composition and pressure of the combustible mixture being such as to produce a short, hot oxidizing flame, the tip of which just reaches the felt, this flame merging into a milder reducing flame which plays upwards for about 6 inches over the felt on the roller. After a short time the bitumen in that part of the felt opposite to the burner will have attained the desired degree of fluidity and tackiness, whereupon the driving motor is started and the pressure rolls are continuously rotated in such a direction that the felt and board are fed between them towards the dis-

charge end of the lower path. Additional plaster boards are fed into the apparatus by being placed successively on the lower path at the entry end thereof, pushed laterally against the fence 110 and thereafter longitudinally towards the pressure rolls, which is possible owing to the overrunning action of the free wheel clutches in the drives to the individual rollers 14A, to form a continuous series of boards touching end to end. In Figs. 1, 2, 3, 5 and 6 the plaster boards are denoted by B and the bitumen felt strip by S. The operator at the discharge end of the lower feed path severs the felt along the junctions between plaster boards by means of a hot knife, so that the coated boards can be handled individually. The leading board of the series will have a length of a few inches of felt not adhering to the board. This length is caused to adhere by passing a hot iron or a torch flame between the loose flap of felt and the board and thereafter pressing this portion of felt onto the board.

The machine runs satisfactorily at a linear speed of about 10 feet per minute with a bitumen felt of usual quality. As the felt strip S is drawn off the roll 40 by the action of the pressure rollers, it unwinds with a resistance which is irregularly distributed over its width, and the felt strip in consequence tends to deviate from the desired alignment. However, passage of the felt under the tensioning bar 45 imposes an additional and substantially uniform resistance which tensions the felt, during its passage over the upper feed path, sufficiently to limit its meanderings to within the limit permitted by the fences 33 and 34. The axis of the roll 40 is spaced at a distance equal to at least three and preferably four times the width of the felt from the roller 106 of the stretching device, and this length is sufficient to allow the irregularities in the tension, due to local sticking of the felt during un-winding, to cancel one another out sufficiently to enable the felt web to run truly onto the first roller 106 of the stretching device, which sets the web in accurate alignment with the plaster boards. The additional tension imposed by the stretching device normally ensures that the felt web maintains its true course round the roll 46. Furthermore the stretching device imposes such an additional resistance to movement of the felt that the felt is stretched sufficiently to avoid risk of subsequent corrugation.

As the felt passes onto and is bent round the surface of the upper roll 46 and approaches the gap between the rolls, the reducing portion of the flame effects a preliminary softening of the bitumen on the exposed face of the felt, which is finally brought by the hot oxidizing portion of the flame to the state of fluidity necessary for proper adhesion to be secured between the felt and the boards as they pass together between the rolls. The upper surface of the boards in passing beneath the flame is preheated sufficiently to prevent premature hardening of the tacky surface of the bitumen when it meets the boards and in this way the strength of the bond is increased. Meanwhile the other face of the felt in the heating zone is kept relatively cool by reason of its intimate contact with the roll 46 which is artificially cooled by both the water passing through its interior and the moisture applied to its exterior by the felt wiper strip 17.

As the tacky surface of the bitumen felt is firmly pressed and bonded to the boards by the pressure rolls, it may happen from time to time that a little fluid bitumen exudes at the side edges of the

boards, or penetrates through the felt or between adjacent plaster boards and is deposited on the rolls. The scraper blades 71 and 88 remove this bitumen from the rolls, such removal being facilitated by the moist condition of the roll surfaces.

With felt rolls of a convenient size, amounting to a length of about 75 feet of felt, fresh rolls have to be brought into use at intervals of about 7½ minutes; and an important property of the present apparatus is that it can be operated without interruption due to the exhaustion of a roll of felt. Before a felt roll is used up, a fresh roll, mounted on a spare shaft 39, with the wedging and locating collars 41 and 43 properly adjusted, is placed on the frame bars 23 and 24 adjacent to the roll in use. As soon as the latter roll is used up, its shaft is lifted out of the bearings 37 and 38, the spare shaft carrying the fresh roll is substituted, and the leading end of the new length of felt is passed under the tension bar 45. The trailing part of the old length of felt, after disengagement from the shaft 39, in being deflected past the elements 105, 106 and 113 of the stretching device, is still stretched and maintained in sufficient tension as it passes from the stretching device to the roll 46. In splicing the leading end of the fresh roll to the trailing end of the preceding roll, it is important to provide an overlapping joint of such a width as to ensure not only a strong and durable bond capable of withstanding, during its passage through the apparatus, the tension and stretching hereinbefore described, but also perfectly formed watertight joints on both sides of the felt web. Experience has shown that to accomplish this the overlap should be preferably between 6 and 12 inches.

The splicing is performed as follows. The leading end of the fresh length of felt is drawn over the trailing end of the preceding length by a distance equal to the required overlap and held in contact therewith while these ends are travelling along the floor 29 of the upper feed path. A hot iron or a torch flame is passed across the width of the felt web between the leading border portion of the fresh length and the underlying part of the preceding length so as to render the bitumen tacky. The tacky surfaces, which may extend through the leading half of the length of the overlap, are immediately thereafter pressed together on to the floor 29 so that the two lengths of felt are firmly bonded together, the last few inches of the preceding length forming a trailing flap on what is at present the under side of the felt web. As the splice passes adjacent to the burner, the whole of the exposed surface of the web is heated by the flame to a condition in which the bitumen thereon is tacky, and, as the splice passes between the pressure rolls, the handle 65 is manipulated so as to increase the gap between these rolls only for so long as is necessary to allow the splice to pass and to such an extent as to maintain the bonding pressure as uniform as possible. When the splice is passing along the lower feed path, a hot iron or a torch flame is passed between the trailing flap constituted by the end of the preceding length of felt, which end is now uppermost, and the underlying felt of the fresh length that is bonded to the plaster boards, in order to render the bitumen tacky, and this trailing flap is then pressed onto the underlying felt so as to complete the bonding of the joint.

The stretching device, through which the felt passes immediately before reaching the pressure rolls and which includes the roller 106 that is arranged to locate the felt web accurately in a

transverse direction, can be swivelled about the pin 119, by unlocking and manipulating the lever 122, in order to correct any errors that may begin to occur in the alignment of the felt web with the plaster boards. Such errors are most likely to arise as a consequence of splicing a fresh length of felt, because it is very difficult to ensure that the two lengths are joined at an angle of exactly 180 deg. If there is a slight deviation of the felt web at the splice, there will be a tendency for the web to run towards one side or the other of the machine as it passes round the upper pressure roll so that one longitudinal edge of the felt will overlap the corresponding edge of the series of plaster boards while the other edge of the felt is spaced inwards from the corresponding edge of the boards. Such tendency for the felt web to run to one or the other side of its true alignment can be corrected, before it has objectionable consequences, by unlocking the swivelling lever 122, moving it in the appropriate sense from its neutral position, and returning it to the neutral position as soon as the felt web is running true again.

25 It has been found that, even in a single roll of bitumen felt, the readiness with which the bitumen will liquefy under the flame varies along the length of the web, owing principally to lack of uniformity in the bitumen content of the felt and 30 in the coating of powder applied thereto to reduce sticking in the roll. An experienced operator can compensate for such variation by slight adjustment of the burner tube control handle 132 so as to cause the flame to strike the felt at a level varying according to his judgment.

I claim:

1. Apparatus for applying to the surface of a series of substantially flat articles a continuous web of flexible sheet material comprising a substance which becomes tacky when heated, said apparatus including a lower feed path for guiding substantially horizontally the series of articles disposed end to end, a pressure roll disposed transversely above said path, an upper feed path 40 for guiding said web towards the top of said roll around which the web passes to be pressed into engagement with the series of articles, a device disposed at the end of said upper feed path adjacent to said roll and including a transverse member for deflecting said web and thereby imposing resistance to its feeding motion, said device being capable of pivotal movement about an axis transverse to the plane of that portion of said web approaching said device for the purpose 45 of varying the alignment of said web as it engages said roll, a control member capable of pivoting said device while the apparatus is operating, and means for heating the exposed surface of said web while passing around said roll.

2. Apparatus for applying to the surface of a series of substantially flat articles a continuous web of flexible sheet material comprising a substance which becomes tacky when heated, said apparatus including a lower feed path for guiding substantially horizontally the series of articles disposed end to end, a pressure roll disposed transversely above said path, an upper feed path 50 for guiding said web towards the top of said roll around which the web passes to be pressed into engagement with the series of articles, a pivotally mounted device disposed at the end of said upper feed path adjacent to said roll and including a plurality of transverse members which are normally parallel to the axis of said roll and being 55 tween which the web passes in zig-zag formation,

lateral guide means for the web on one of said transverse members, and a control member operable while the apparatus is working for pivoting the device in such a manner as to cause said transverse members, when viewed perpendicular to that portion of the web between said device and said roll, to diverge from said axis towards either side of the apparatus at will, and means for heating the exposed surface of said web while passing around said roll.

3. Apparatus for applying to the surface of a series of substantially flat articles a continuous web of flexible sheet material comprising a substance which becomes tacky when heated, said apparatus including a lower feed path for guiding substantially horizontally the series of articles disposed end to end, two cooperating rolls respectively above and below said path, an upper feed path including guide fences at each side for guiding said web towards the top of the upper of said rolls, means for supporting a rolled length of sheet material while it is being unwound onto said upper feed path, a transverse member associated with said upper feed path and positioned to deflect the unrolling web onto said upper feed path, at least one transverse member capable of being pivoted by a control member about an axis transverse to the surface of said upper path and positioned to deflect the web between said upper path and the upper of said rollers, around which the web is deflected into contact with the series of articles, and means for heating the exposed surface of said web while passing round said upper roll.

4. Apparatus for applying to the surface of a series of boards a continuous web of bitumen felt, said apparatus comprising a roll, means for guiding said series of boards past said roll, means for guiding said web onto said roll, around which it runs into engagement with said series of boards, means disposed adjacent to said roll for heating the exposed surface of the web while passing round said roll, and means for delivering a film of water to the exterior surface of said roll on the side thereof opposite said heating means to cool the unexposed surface of said web prior to the heating of the exposed surface thereof.

5. Apparatus for applying to the surface of a series of boards a continuous web of bitumen felt, said apparatus comprising a hollow roll, means for guiding said series of boards past said roll, means for guiding said web onto said roll, around which it runs into engagement with said series of boards, means disposed adjacent to said roll for heating the exposed surface of the web while passing round said roll, means for passing a flow of cooling liquid through the interior of said roll and means for distributing a film of cooling liquid over the exterior surface of said roll on the side thereof opposite said heating means to cool the unexposed surface of said web prior to the heating of the exposed surface thereof.

6. Apparatus for applying to the surface of a series of substantially flat articles a continuous web of flexible sheet material comprising a substance which becomes tacky when heated, said apparatus including two co-operating superimposed pressure rolls, means for guiding the series of articles between said rolls, means for guiding the web onto one of said rolls, round part of the circumference of which it passes into contact with the articles as they pass between said rolls, means for heating the exposed surface of the web as it passes round said one of the rolls, means for distributing films of liquid over the surfaces

of said rolls, and two scrapers engaging respectively the surfaces of said rolls.

7. Apparatus for applying continuously to the surface of a series of boards a continuous web of flexible sheet material comprising a substance which becomes tacky when heated, said continuous web being formed from a plurality of separate rolls of the material, said apparatus including a lower feed path for guiding the series of boards placed end to end longitudinally of the apparatus, a pressure roll disposed transversely above said path, an upper feed path having a floor and serving to guide the web towards the top of said roll around which the web passes into engagement with the series of boards, means for heating the exposed surface of the web while it is passing round said roll, means for supporting a shaft carrying a supply of the flexible sheet material in position for the web to unwind therefrom onto said upper feed path, said supporting means permitting instantaneous removal and replacement of said shaft, a web-stretching device disposed between said upper path and said roll for tensioning the trailing portion of one length of the material while it is being joined to the leading end of a fresh length on said floor, and means for swivelling said stretching device in order to correct errors in the alignment of the web.

8. Apparatus for applying a continuous web of a bitumen felt, to a series of boards disposed end to end, said apparatus including a pair of rolls disposed one above the other, a roller path on the entry side of said rolls for guiding the series of boards between them, a second path on the discharge side of said rolls for guiding said web onto the upper one of said rolls around which it passes into engagement with said boards, transverse members associated with said second path and so positioned as to impart to the web a zig-zag formation whereby it is tensioned while approaching said rolls, means operable for displacing at least one of said transverse members relatively to the remainder for varying the acuteness of the zig-zag formation within a range capable of effecting a permanent elongation of the bitumen felt web, heating means disposed adjacent to said roller path and said upper roll for heating said web after its engagement with said upper roll and immediately before it is pressed by said rolls into engagement with said boards, and means for artificially cooling said upper roll to cool the unexposed surface of said web.

9. Apparatus for applying to the surface of a series of boards a continuous web of bitumen felt, said apparatus including a lower feed path for guiding substantially horizontally the series of boards disposed end to end, a pressure roll disposed transversely above said path, an upper feed path including a floor having lateral guide fences and serving to guide said web substantially horizontally towards the top of said roll in a direction opposite to the direction of feeding of said boards, so that said web can pass around part of the circumference of said roll into engagement with the upper surface of said series of boards, means for supporting a rolled length of bitumen felt while it is being unwound onto said upper feed path, at least two members disposed transversely of said upper feed path respectively at the entry to and at the exit from said fences for deflecting said web and thereby imposing resistance to its feeding motion both as it approaches and as it leaves said fences, said rolled length and the one of said transverse members nearer said pressure roll being spaced apart by a distance equal to at

least three times the width of said web, and said one transverse member including lateral guides for aligning said web as it passes onto said roll, and means disposed adjacent to said roll for heating the exposed surface of said web while passing around said roll.

10. Apparatus for applying to the surface of a series of boards a continuous web of bitumen felt, said apparatus including a roll, a substantially horizontal lower feed path for guiding a series of boards beneath said roll, a substantially horizontal upper feed path for guiding said web onto said roll, in a direction opposite to the direction of feeding of said boards, so that said web will pass part way round said roll into engagement with said boards, a movable burner extending parallel to said roll and close above the part of said lower feed path approaching said roll, said burner being capable of directing a line of flame towards the exposed surface of the web while passing round said roll, and a control member for moving said burner while it is operating so as to vary its heating effect on the web.

11. Apparatus for applying to the surface of a series of substantially flat articles a continuous web of flexible sheet material comprising a substance which becomes tacky when heated, said apparatus comprising a roll, means for guiding said series of articles past said roll, means for guiding said web onto said roll, around which it runs into engagement with said series of articles, a tube perforated along a portion of its circumference and disposed parallel to said roll near the exposed surface of said web passing round said roll, said tube being angularly displaceable about its axis, means for supplying a combustible gaseous mixture to said tube, and a control member operable for angularly displacing said tube and thereby varying the heating effect, on said exposed surface of the web, of flames projected by said perforated portion of the tube.

12. Apparatus for applying to the surface of a

series of boards a continuous web of bitumen felt, said apparatus including two co-operating pressure rolls at least one of which is hollow, means for guiding the series of boards disposed end to end between said rolls, means for guiding the web onto said one roll, round part of the circumference of which it passes into contact with the boards as they pass between said rolls, means disposed parallel to said one roll adjacent to the path of entry of said boards between said rolls for heating the exposed surface of the web as it passes round said one roll, means for continuously distributing a film of water over said one roll, a scraper resiliently engaging the surface of said one roll, and means for passing a flow of cooling water through said one roll.

13. Apparatus for applying a continuous web of a flexible material, comprising a substance which becomes tacky when heated, to a series of boards disposed end to end, said apparatus including a pair of rolls disposed one above the other, a substantially horizontal roller path on the entry side of said rolls for guiding the series of boards end to end between them, a substantially horizontal path having a floor on the discharge side of said rolls and placed at a higher level than said roller path for guiding said web towards the top of the upper one of said rolls around part of the circumference of which it passes into engagement with said boards, the length of said floor being at least three times the width of the web, heating means disposed adjacent to said roller path and said upper roll for heating the exposed surface of the web immediately before it is pressed by said rolls into engagement with the boards, means for artificially cooling said upper roll to cool the unexposed surface of said web, and a continuation of said roller path on the discharge side of said rolls extending beyond the beginning of said upper path.

JOSEPH FRANCIS STRABLE.
